(57) **CLAIM**

The ornamental design for a display screen with a graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a display screen with a graphical user interface showing a first image of the claimed design; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a seventh image thereof; FIG. 8 is an eighth image thereof; FIG. 9 is a ninth image thereof; FIG. 10 is a tenth image thereof; FIG. 11 is an eleventh image thereof; FIG. 12 is a twelfth image thereof; FIG. 13 is a thirteenth image thereof; FIG. 14 is a fourteenth image thereof; FIG. 15 is a fifteenth image thereof; FIG. 16 is a sixteenth image thereof; FIG. 17 is a seventeenth image thereof; FIG. 18 is an eighteenth image thereof; FIG. 19 is a nineteenth image thereof; FIG. 20 is a twentieth image thereof;

(Continued)

FIG. 21 is a twenty-first image thereof;
 FIG. 22 is a twenty-second image thereof;
 FIG. 23 is a twenty-third image thereof;
 FIG. 24 is a twenty-fourth image thereof;
 FIG. 25 is a twenty-fifth image thereof;
 FIG. 26 is a twenty-sixth image thereof;
 FIG. 27 is a twenty-seventh image thereof;
 FIG. 28 is a twenty-eighth image thereof;
 FIG. 29 is a twenty-ninth image thereof;
 FIG. 30 is a thirtieth image thereof;
 FIG. 31 is a thirty-first image thereof;
 FIG. 32 is a thirty-second image thereof;
 FIG. 33 is a thirty-third image thereof;
 FIG. 34 is a thirty-fourth image thereof;
 FIG. 35 is a thirty-fifth image thereof;
 FIG. 36 is a thirty-sixth image thereof;
 FIG. 37 is a thirty-seventh image thereof; and,
 FIG. 38 is a thirty-eight image thereof.

The appearance of the transitional image sequentially transitions between the images shown in FIGS. 1-38. The process or period in which one image transitions to another image forms no part of the claimed design.

The outer perimeter broken line showing of a display screen forms no part of the claimed design. All other broken lines show portions of the graphical user interface that form no part of the claimed design.

The “WeatherMax,” “SIMPLEconnect,” and “SURE-SPEED” trademarks forming part of the claimed design are registered trademarks of Hunter Fan Company.

How to choose a ceiling fan

To help you to choose your needs, a better ceiling fan adds more decorative touch, but this doesn't together to become complete. A variety of ceiling fan designs and colors and light treatments, decorative and decorative ceiling fans are available. When you buy ceiling fans, you may be wondering how to choose a ceiling fan for your needs.

Whether you're installing a fan in a single room, renovating your entire house, or remodeling a room that needs a complete refresh, this ceiling fan buying guide can help you pick a ceiling fan with confidence.

Table of Contents

1. Choosing a location for your fan
2. Choosing the right ceiling fan size
3. Fans & lighting: Fan types
4. Choosing ceiling fans based on your room's lighting needs
5. Choosing ceiling fans based on your room's color palette
6. Choosing ceiling fans based on your room's architectural style
7. Choosing ceiling fans based on your room's needs
8. Choosing ceiling fans based on your room's needs

FIG. 1

How to Choose a Ceiling Fan

With so many ceiling fan sizes to choose from, you may be wondering how to choose the right ceiling fan for your space. Hunter's here to help you choose with confidence.

Determine the Fan's Location

Indoors

- Keep your home feeling cool in the summer.
- Distribute heat throughout your home in the winter.
- Terminated rated fans because they are only designed for indoor use.

Outdoors

- Outdoor fans can be damp rated for covered porches, or wet rated for pergolas.
- Hunter's WeatherMax® fans are wet rated fans corrosion and salt air resistant.

FIG. 2

EIG

FIG. 6

FIG. 7

Airflow and Efficiency

Do you need
high-speed cooling?

WHY CHOOSE A HUNTER SURESPEED® FAN:

- Powerful air velocity with uniform flow to effectively cool you.
- Whisper-quiet and wobble-free.
- High-speed cooling airflow can be felt throughout your space.
- Energy-efficient with higher airflow while consuming less energy.

FIG. 8

FIG. 9

Where will you install your ceiling fan?

Residence or Business

When choosing a ceiling fan size and design for your space, location matters.

Residential Ceiling Fans

Hunter creates residential ceiling fans designed to go with every lifestyle, decorative theme and a variety of styles ranging from traditional to modern are ready to instantly upgrade the look of your home.

Industrial Ceiling Fans

Our industrial ceiling fans are designed to increase airflow while reducing energy consumption. These high-volume, low-speed (HVL) fans are especially designed and calculate air more than any other type of traditional ceiling fan on the market. Hunter industrial fans provide super-quiet performance and our impressive fan warranties are among the best in the industry.

How to choose an indoor/outdoor ceiling fan

Indoors

When temperature is in the 60s, a ceiling fan can keep your home feeling cool. During a big weather's heating, fan can substitute heat throughout your home, too. While some indoor fans can be used indoors, indoor fans cannot be used outdoors.

An indoor fan is sometimes referred to as a desk fan, because it is used for a King room or bedroom. Rated only for indoor use, some day-rated fans, such as kitchen, shed, water, separate or marine, do, may not be the best choice for bathrooms and laundry rooms. And, definitely do not place them outside.

Outdoors

When choosing a ceiling fan for an outdoor space, pick a model with the appropriate Underwriters Laboratories (UL) and Electrical Testing Laboratories (ETL) rating. Otherwise, technical difficulties with the fan can arise. For example, if the fan isn't rated for the proper type of outdoor use and it's exposed to humidity or rain, pieces of the fan could rust and impact operation.

UL and ETL ratings can be broken down into two general categories: damp rated and wet rated. Use the following information to help you determine which outdoor ceiling fan may best suit your outdoor space.

[SHOP OUTDOOR FANS](#)

FIG. 12

1. Location   2. Size   3. Style   4. Lights   5. Mount-type   6. Control   7. Airflow/efficiency   8. Budget

Damp-rated fans

Damp-rated fans are designed for use in covered outdoor spaces, like covered patios or porches, or inside places like bathrooms and laundry rooms that aren't directly exposed to water but may come in contact with humidity. These fans withstand exposure to moisture and are constructed with rust-resistant stainless steel.

Wet-rated fans

Wet-rated fans are designed for use in outdoor spaces that may be exposed to elements like heavy snow or rain. Ideal for gazebos and pergolas, our wet-rated fans are engineered to withstand direct contact with water and moisture. These fans are built with rust-resistant motors and all-weather blades for long-lasting and safe performance.

WeatherMax® fans

Hunter WeatherMax® fans are built for the outdoors with features and technologies that go beyond the average wet-rated models. WeatherMax designs are corrosion- and salt-air-resistant, perfect for beach properties or homes that get a lot of salt from snow trucks, while also featuring our SureSpeed® guarantee for high-flow-velocity performance.

What size ceiling fan do you need?

For maximum efficiency, choose an appropriate ceiling fan size for each room. Installing a fan that's too small for the space won't circulate air effectively to make the room feel cool. Alternatively, if you install a fan that's too large for the space, it could overpower the room, even on a lower setting. Use our ceiling fan size guide to determine what size ceiling fan you need for your room.

Fan diameter for room size

The amount of air circulated by a ceiling fan is determined by its diameter. Larger spaces require fans with larger diameters, while smaller spaces require fans with smaller diameters.

Small rooms

300 square feet or less work best with a small ceiling fan that range from 30 inches to 48 inches. Small diameter fan sizes are ideal for home offices and study rooms.

Large rooms

400 square feet or less work best with medium ceiling fans that range from 48 inches to 54 inches. Medium diameter fan sizes are ideal of living rooms, bedrooms, and kitchens.

Great rooms

Over 400 square feet work well with large ceiling fans 56 inches or larger. Large diameter ceiling fans are ideal for open-concept living areas or lofts with ample space.

Modern

With their sleek designs, clean lines, and warm, neutral colors, modern ceiling fans are simple and understated in appearance. Modern fans vary in form from Scandinavian to mid-century designs.

Traditional

These refined fans typically feature intricate details and graceful designs that add richness and warmth to a space. Our traditional ceiling fans blend classic style and innovative features.

Rustic

An ideal addition to country-style, inspired designs, rustic ceiling fans create a natural feel. Cast iron-inspired housings and weathered blades bring cabin-like charm into the home and outdoor living spaces.

Industrial

Industrial style ceiling fans bring urban-inspired spaces to life drawing inspiration from modern machinery and unique features like propeller-style blades or smooth wood finishes.

FIG. 19

1. Location   2. Size   3. Style   4. Lights   5. Mount-type   6. Control   7. Airflow/efficiency   8. Budget

Contemporary

Contemporary ceiling fans are for those looking for a fixture that makes a statement as soon as you walk into the room. These fans push the boundaries of ceiling fan design and look like a work of art.

Farmhouse

Popular farmhouse ceiling fans create a warm and cozy atmosphere that combines the comfort of rustic living with the benefits of updated modern design for a style that stands the test of time.

FIG. 20

1. Location	2. Size	3. Style	4. Lights	5. Mount-type	6. Control	7. Airflow/efficiency	8. Budget

Blade and housing finishes

Ceiling fan colors and housing finishes set the tone of your space. For example, white ceiling fans complement most ceilings and instill a classic finishing touch to any room. Black ceiling fans make a bold statement, bringing an edgy and sophisticated look to spaces. Brass finishes and brushed nickel complement other hardware in your room. Finishing touches like ceiling fan glass shades and fan caps and finials also help refine the look of a fan and tie the overall design scheme together.

STEP 4.

Lights or no lights?

Fans Without lights

If you plan to install your new fan in a room with good natural lighting or ample light from other sources, a ceiling fan without lights is a good option.

If you decide that you need more lighting in the future, many ceiling fan models can be easily modified after installation with the appropriate light kit.

[SHOP FANS WITHOUT LIGHTS](#)

FIG. 22

1. Location	2. Size	3. Style	4. Lights	5. Mount-type	6. Control	7. Airflow/efficiency	8. Budget

Fans with lights

For spaces with limited natural lighting, purchasing a ceiling fan with lights is a great option to consider. Ceiling fans with light kits can be supplemented with other fixtures to provide sufficient illumination in darker spaces.

When looking for ceiling fans with lights, check for integrated light dimming features. Ceiling fans with dimmable lights allow you to set the mood in your space. Our wall controls and handheld remotes make the process of adjusting your lighting easy, too.

[SHOP FANS WITH LIGHTS](#)

+ Types of bulbs

Today's fans offer a wide array of lighting sources, including several energy-efficient options. Here's a breakdown of some of the most common types of lighting bulbs to consider:

LED

With an average life span of 50,000 hours, LED bulbs are the most energy-efficient option on the market. There are also a variety of LED bulbs found in ceiling fans today, more traditional bulbs, Edison bulbs with glowing filaments, and integrated LED discs that are designed to never need charging.

Fluorescent

These light bulbs have an average life span of 10,000 hours and use less energy than incandescent bulbs.

Halogen

With an average life span of 1,500 hours, halogen bulbs emit a warm light and use around 15-percent less energy than incandescent bulbs.

- Number of bulbs
- Purpose of lighting
- Task vs. ambient lighting

1. Location   2. Size   3. Style   4. Lights   5. Mount-type   6. Control   7. Airflow/efficiency   8. Budget

- Types of bulbs

+ Number of bulbs

The number of bulbs a ceiling fan features influences the lighting ambience of the space. For example, ceiling fans with single bowl light kits are ideal for larger spaces that require medium-level ambient lighting such as bedrooms, offices, kitchens, and living rooms.

For spaces where no other lighting is provided, fans with ambient lighting are a great option. These ceiling fans often feature three to four bulbs depending on their design. Their multiple bulbs spread light across the space, brightening the entire room.

- Purpose of lighting

- Task vs. ambient lighting

- Functional, single-source lighting vs. decorative lighting

- Types of bulbs
- Number of bulbs
- Purpose of lighting
- + Task vs. ambient lighting
  - | Task lighting provides smaller, more concentrated light that's meant to increase visibility for projects like reading, working, and cooking. Ambient lighting produces a soft glow that illuminates a space enough for you to see while maintaining a warm tone.
- Functional, single-source lighting vs. decorative lighting

FIG. 28

1. Location   2. Size   3. Style   4. Lights   5. Mount-type   6. Control   7. Airflow/efficiency   8. Budget

- Types of bulbs
  - Number of bulbs
  - Purpose of lighting
  - Task vs. ambient lighting
- + Functional, single-source lighting vs. decorative lighting

Functional, single-source lighting provides a space with overall illumination. In rooms where lighting is limited, a ceiling fan that provides the main source of functional lighting is fundamental to a lighting scheme. In spaces where your primary goal is to accentuate decorative elements, a ceiling fan with an integrated downlight kit creates a clean and sophisticated look that won't overpower the other lighting in the room.

FIG. 29

**Which mount-type works
best for your space?**

Ceiling fan mounting and
downrod options

FIG. 30

1. Location   2. Size   3. Style   4. Lights   5. Mount-type   6. Control   7. Airflow/efficiency   8. Budget

Flush-Mount / Low-Profile

Intended for rooms with ceiling heights around eight feet high, flush-mount applications are ideal. These low-profile ceiling fans are designed to install flush with the ceiling so the blades hang at a safe distance overhead.

Standard

Ceiling fans with a standard mount are designed for rooms where the ceiling height is around nine feet. The use of a ceiling fan downrod during installation ensures the appropriate hanging height of eight to nine feet from the floor.

High and Vaulted Ceilings

When the ceiling height is greater than 10 feet, fans may need to be mounted without the use of an extended downrod. For sloped or vaulted ceilings exceeding 34 degrees, a sloped ceiling adapter kit must be used to ensure proper ceiling fan installation. This type of adapter replaces the ceiling fan canopy that comes with your fan.

FIG. 31

FIG. 32

1. Location   2. Size   3. Style   4. Lights   5. Mount-type   6. Control   7. Airflow/efficiency   8. Budget

STEP 6.

How do you want to control your fan?

Control your fan based on your preferences by choosing a control system that's convenient and works best for you. Simple ceiling fan controls rely on a wall switch that lets you turn the fan on and off and adjust its speed with a pull chain switch. Hunter's more advanced ceiling fan control systems allow you to control the fan's settings from a wall control or

Ceiling fan remote and controls

SHOP FANS WITH REMOTES

FIG. 33

1. Location 2. Size 3. Style 4. Lights 5. Mount-type 6. Control 7. Airflow/efficiency 8. Budget

Pull chains

For rooms with lower ceilings where you're able to reach a pull chain, a ceiling fan with a pull chain is a great option. Pull chains also work well for outdoor closed spaces so you have the option of adjusting the speed without needing a remote.

Wall control

Control your fan's direction and speed and easily dim the lights with the push of a button using a Hunter wall control. This type of control is mounted inside the wall light switch, which makes it simple to always remember where your ceiling fan control is located.

Remote control

A handheld remote offers increased convenience and comfort. Hunter ceiling fans with remotes let you dim the lights and adjust the fan's direction and speed with one easy-to-use device from wherever you are in the room. Simply keep the remote next to you on the coffee table or nightstand or use the included cradle to hang on your wall.

Smart home control

Hunter's SIMPLEconnect® Collection of Wi-Fi-enabled ceiling fans let you adjust your fan's settings using your smart device with our SIMPLEconnect app or via the included handheld remote. Use our ceiling fan smart home technology and your favorite home automation system to conveniently operate your fan.

STEP 7.

What airflow/efficiency do you need?

How to Choose a Ceiling Fan Size & Style | Hunter Fan

Since a ceiling fan can help make a room feel six to eight degrees cooler in the summer, your air conditioner won't have to work as hard to cool your home. In the winter, by running your fan in a clockwise position on low speed, warm air will be pushed down and recirculated without creating a cooling effect.

Airflow you can feel

With optimized motors and precision blades, Hunter SureSpeed fans produce powerful air velocity while remaining whisper-quiet and wobble-free. The contoured, aerodynamic design of the blades on a SureSpeed fan produces a more uniform flow of air to effectively cool you. This means more of the high-speed cooling airflow can be felt throughout your space.

What's your budget?

Fans for every space and budget

Hunter designs ceiling fans for every space and budget. Shop our fans by price to find a fit that's perfect for your needs and budget, or explore a variety of stunning luxury designs in our Casablanca line of ceiling fans.

The innovative designs and pioneering technology of Hunter bring new life into any space. Committed to excellence, we conduct twice the amount of industry-standard testing on each ceiling fan to ensure best-in-class performance. The above guide will help you navigate how to choose a ceiling fan that perfectly suits your preferences.
